REMOVABLE CORE LOCK

Mathias M. Check, Valley Forge, Pa., assignor to The Yale and Towne Manufacturing Company, Stamford, Conn., a corporation of Connecticut

Filed Apr. 14, 1959, Ser. No. 806,362

5 Claims. (Cl. 70—369)

This invention relates to a removable lock core of the type having a key-operated plug and tumblers with the plug rotatable relatively to the core when released. This core is adapted for insertion and removal relatively to a housing, the housing being generally of a cylindrical configuration assembled to a lock. In locks of the particular class, insertion of one key will merely effect the release of the key plug so that it may rotate relatively to the cylinder lock core to retract a latchbolt or to control a bolt, depending on the lock construction. Insertion of a second key will set the tumblers in a manner to permit the operation of a retaining member that normally holds the lock core within the cylindrical housing.

The purpose of locks of the particular class is to permit ready removal and insertion of the lock core relatively to the lock housing so that it is easy to change the lock core when that becomes desirable, as in the event it is desired to change keys. Those skilled in the art will readily appreciate that the combination that I have thus set forth broadly is old in the art, and is shown in numerous patents.

So far as I know, the problem of a suitable retainer for a lock core has always confronted the art. In other words, it is exceedingly difficult to develop a retainer that may be operated with facility, and yet will be positive, rap-proof, and easily controlled so as to permit the ready insertion and removal of the lock core.

As a feature of my invention, I utilize a retainer that is actuated through the simple rotation of the key plug alone, by the mere setting of the regular tumblers, thereby eliminating the need for a special sleeve or other means required by the prior art. This obviates the need for discs or cut tumblers to be set by a special key bitting. Those skilled in the art realize that discs and cut tumblers decrease security and make it possible for lockouts to occur.

As a feature of my invention, I utilize a pin or the like carried by the key plug, but not projected from the key plug until set by a special key. Upon being set by a special key, the pin is projected so as to act as a detent and to move retainer from a retaining to a release position. The construction set forth may be mounted at the end of the lock core with the pin actuated by the end of the key, thereby making possible the placing of the retainer in a position where it may function best. Moreover, it is possible to form within the housing a slot or surface cooperable with the retainer, without unduly complicating the manufacture of the retainer.

As a further feature of the invention, the retainer, while spring pressed into locking position relatively to the cylinder housing, is not movable out of retaining position against the pressure of the spring until the key plug is rotated. More particularly, there is between the key plug and the retainer a connection that permits free rotation of the key plug relatively to the retainer but prevents movement of the retainer out of retaining position except when the key plug rotates. This prevents the rap-

2

ping of the detent out of locking position as those skilled in the art will well appreciate.

As a still further feature of my invention, I utilize a novel form of cam on the end of the key plug of my core, making it possible to remove the core with the cam still secured thereto.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

My invention having been broadly described, a more detailed description of one embodiment of the invention is given hereafter by reference to the accompanying drawings wherein:

FIG. 1 is a front view of a lock assembly incorporating my invention, showing the housing, removable lock core, and key plug;

30 FIG. 2 is a sectional view taken on the line 2—2 of FIG. 1, showing the pin for actuation of the retainer in retracted or non-actuating position within the key plug;

FIG. 3 is a partial sectional view similar to that of FIG. 2, but showing the pin for actuation of the retainer in projected or actuating position;

35 FIG. 4 is an enlarged rear view of the lock cylinder assembly, showing the latch cam which is secured to the end of the key plug;

FIG. 5 is also a rear view of the lock assembly similar to that of FIG. 4, but showing how the end of the latch cam is notched to permit removal of the lock core when the key plug has been turned approximately 15°;

40 FIG. 6 is a sectional view taken on the line 6—6 of FIG. 3, showing the pin projected into the retainer by insertion of a special key preparatory to rotating the key plug to cam the retainer out of the slot in the housing to permit removal of the lock core;

FIG. 7 is a sectional view similar to that of FIG. 6, but showing the retainer cammed out of the slot in the housing to permit removal of the lock core, and

50 FIG. 8 is a perspective view showing the lock core removed from the housing.

Referring to the drawings, and in particular to FIG. 2, the lock includes a housing 10, a lock core 11, and a key plug 12. The lock core 11 is slidably received within the housing 10 and the key plug 12 rotatable within the lock core 11 upon proper setting of tumblers 13 by a key of the proper bitting. The tumblers 13 are loaded by conventional drivers 14 and springs 15. A latch cam 16 is secured to the end of the key plug 12 by screws 17 and is rotatable with the key plug 12 to retract a latch bolt or to control a bolt, depending on the lock construction. The housing 10 is provided with a threaded end 10a, so that it may be secured to the usual lock case.

60 As so far described, the lock assembly is of generally

conventional construction. The lock, however, differs from conventional construction in the provision of an extra pin or tumbler 18 which in retracted position is contained within the key plug, but which may be projected by a key K of proper length and bitting to engage in a slot 19a in a pivotally mounted retainer 19, as best shown in FIGS. 3 and 6. The retainer 19 is pivoted within the lock core 11 on a pin 20 and is of a size to be contained completely within the lock core 11 in retracted position and to extend beyond the outer surface of the lock core 11 in extended position. When the lock core 11 is completely inserted in the housing 10 and the retainer 19 extended, the edge of the retainer is received in a slot 21 in the housing 10 to lock the core within the housing 10, as best shown in FIG. 6. To remove the lock core 11, a key K of proper length and bitting to set the tumblers 13 and to project the pin 18 is inserted in the key slot 12a of the key plug 12 and the key plug 12 rotated. As the key plug 12 is thus rotated, the pin 18 cams the retainer 19 out of the slot 21 as shown in FIG. 7, thereby permitting the lock core to be withdrawn from the housing as shown in FIG. 8.

As best shown in FIG. 5, the latch cam 16 is secured to the key plug 12 and to permit its removal with the lock core 11, it is notched at 16a. The conventional shape of the cam is shown in dotted lines, and it will be appreciated that without the notch 16a the cam 16 would prevent removal of the lock core 11. Having the cam fixed to the key plug permits it to be replaced or repaired, should it become worn or damaged.

Preferably the retainer 19 is provided with a spring 22 which engages the wall of the housing and urges the retainer 19 to extended position. The spring 22 is not necessary, however, as the retainer 19 is moved positively in both directions by the pin 18 to insure that the retainer is fully released from or engaged with the housing 10. However, the spring 22 does help to prevent the retainer 19 from vibrating out of alignment and remaining so, if there should be a binding or sluggish action due to dirt or some other restricting cause.

A projecting lug 23 on the edge of the retainer 19, as shown in FIGS. 6 and 7 meshes with a notch or cut-out 24 in the key plug 12, so that the retainer 19 cannot be rotated out of locked position without simultaneous rotation of the key plug 12. This prevents disengagement of the retainer by rapping.

A second projection 25 on the retainer 19 engages the surface of the key core and prevents excessive rotation of the retainer 19 after the retainer is disengaged from the slot 21.

From the above description it can be seen that I have provided an improved cylinder lock in which the lock core may be easily and quickly removed by a mere setting of the regular tumblers and rotation of the key plug. This eliminates the need for a special sleeve or other means which have heretofore been deemed necessary to provide a removable lock core. The invention also obviates the need of discs or cut tumblers to be set by special key bitting.

While one embodiment of the invention has been shown and described, it will be appreciated that changes and modifications can be made therein without departing from the spirit and scope of the invention.

I now claim:

1. In a combination of the class described, a lock housing, a lock core slidable in and out of said housing, a key plug rotatable relative to said lock core upon the setting of a series of tumblers, a retainer mounted on said lock core for extension beyond the outer surface of said lock core, means on said lock housing engageable with said retainer when said retainer is in an extended position to thereby lock said lock core in said housing, means extendable from said key plug to a position in laterally opposed relationship with a portion of said retainer and engageable with said portion of said retainer to

retract said retainer upon rotation of said key plug to thereby permit removal of said lock core from said housing, and cooperating means on said retainer and on said key plug providing opposed surfaces engageable to prevent disengagement of said retainer from said means on said lock housing except when said key plug is rotated.

2. In a combination of the class described, a lock housing, a lock core adapted to slide in and out of an opening in said housing conforming to the configuration of the lock core, a key plug rotatable relatively to said lock core upon the setting of a series of tumblers, a retainer rotatably mounted on said lock core, a pin carried entirely within said key plug and projectable by a key out of said key plug into a position in laterally opposed relationship with a portion of said retainer whereby a force is applied to said portion of said retainer by said pin upon rotation of said key plug thereafter by said key to effect operation of said retainer, said retainer being rotatable relatively to said core and into and out of a slot formed in said housing when said cylinder lock core is in said housing in alignment with said slot, and a projection on said retainer adapted to mesh with a notch in said key plug whereby said retainer can rotate out of said slot only upon rotation of said key plug.

3. In a combination of the class described, a lock housing, a lock core adapted to slide in and out of an opening in said housing conforming to the configuration of the lock core, a key plug rotatable relatively to said lock core upon the setting of a series of tumblers, a retainer rotatably mounted on said lock core for movement into and out of a slot formed in said housing when said cylinder lock core is in said housing in alignment with said slot, means carried entirely within said key plug and projectable by a key out of said key plug into a position in laterally opposed relationship with a portion of said retainer, whereby rotation of said key plug thereafter by said key forces said projecting means against said portion of said retainer to effect operation of said retainer, and a projection on said retainer adapted to mesh with a notch in said key plug whereby said retainer can rotate out of said slot only upon rotation of said key plug.

4. In a combination of the class described, a lock housing, a lock core slidable in and out of said housing, a key plug mounted for rotation in said lock core, said key plug having a longitudinally extending key slot and a plurality of longitudinally aligned locking tumblers slidably mounted in said key plug with the inner ends of the tumblers extending into said key slot whereby said tumblers may be set by a key inserted into said key slot to allow rotation of the key plug relatively to said lock core, a pin independent of said locking tumblers aligned longitudinally with said locking tumblers and slidably mounted in said key plug with the inner end of said pin extending into said key slot and the outer opposite end of said pin being projectable beyond the outer surface of said key plug by a key inserted in said key plug, a retainer mounted on said lock core for extension beyond the outer surface of said lock core, means on said lock housing engageable with said retainer when said retainer is extended whereby to lock said lock core in said housing, said retainer having a portion thereof in laterally opposed relationship with the outer end of said pin and engageable by said outer end of said pin when said pin is projected from the outer surface of said key plug whereby rotation of said key plug effects operation of said retainer to release said lock core from said lock housing.

5. In a combination of the class described, a lock housing, a lock core slidable in and out of said housing, a key plug mounted for rotation in said lock core, said key plug having a longitudinally extending key slot and a plurality of longitudinally aligned locking tumblers slidably mounted in said key plug with the inner ends of the tumblers extending into said key slot whereby said tumblers may be set by a key inserted into said key slot to allow rotation of the key plug relatively to said lock core,

a pin slidably mounted in said key plug with the inner end of said pin extending into said key slot and an outer end of said pin being projectable beyond the outer surface of said key plug by a key inserted in said key plug, a retainer, pivot means mounting said retainer on said lock core for pivotal extension beyond the outer surface of said lock core, means on said lock housing engageable with said retainer when said retainer is extended whereby to lock said lock core in said housing, said retainer when extended having a portion thereof in laterally opposed relationship with the outer end of said pin and engageable by said outer end of said pin when said pin is pro-

5 jected from the outer surface of said key plug whereby rotation of said key plug pivots said retainer to release said lock core from said lock housing.
